UNITED STATES PATENT OFFICE.

ROLLAND H. MAXSON, OF MILTON, WISCONSIN, ASSIGNOR, BY MESNE ASSIGNMENTS, TO THE BURDICK CORPORATION, OF MILTON, WISCONSIN, A CORPORATION OF DELAWARE.

RHEOSTAT.

Application filed May 5, 1923. Serial No. 636,837.

This invention relates to rheostats.

It will be explained as embodied in a rheostat particularly adapted for the control of electro-therapeutic appliances.

5 One of the objects of the invention is to provide an improved rheostat.

Another object is to provide a rheostat which may be readily manipulated.

Another object is to provide a rheostat 10 which may be suspended by or, in effect, form a part of the current supply cord.

Another object is to provide a rheostat, whose installation in a current supply cord necessitates the cutting of only one of the 15 conductor pairs.

Another object is to provide a rheostat with which various appliances may be readily connected and disconnected.

Another object is to provide a rheostat 20 which is reliable, compact, efficient and may be relatively inexpensively and readily manufactured.

Other objects and advantages will hereinafter appear.

25 Embodiments of the invention are illustrated in the accompanying drawing, wherein

Fig. 1 shows a current conducting cord and one form of rheostat.

30 Fig. 2 is an enlarged longitudinal section of the rheostat shown in Fig. 1.

Fig. 3 is a section on the line 3—3 of Fig. 2, and

Fig. 4 is a longitudinal section of a modified form of rheostat.

As shown in Fig. 1, the rheostat 5 may be located in an ordinary multi-conductor current supply service cord between the source of current and the appliance utilizing 40 the current. The rheostat is employed to vary the current flowing to the appliance.

For convenience of explanation the service cord may be considered as composed of two sections, a supply section 6 for connection 45 to the service mains, and a delivery section

7 for connection to the appliance. The cord sections may be equipped with suitable plug or other desired type of connectors for attachment to the service mains and the appliances. Ordinarily, of course, the two 50 sections of the service cord may be interchangeably connected to the service mains and the appliances so that the designations which hereafter may be used concerning

55 them are to be considered as applied to

interchangeable and operatively synonomous elements.

The rheostat illustrated in Figs. 2 and 3 has a resistor 8, which may consist of a coil of suitable resistance wire wound on a tubular support 9. Support 9 may be formed from suitable insulating material, such as fiber. Resistor 8 is enclosed by a tubular metal shell or housing 10 which may be provided with ventilating openings 11 if desired.

One end of housing 10 is provided with a head 12 which may be secured in place by screws 13. Head 12 has an annular groove 14 in its inner face for receiving one end 70 of support 9. A hole 15 passes substantially axially through head 12 to afford a passage for a section of the service cord.

A contact head 16 of suitable insulating material, such as fiber, is secured in housing 75 10 near the opposite end thereof. Screws 17 will serve to hold this contact head in place. An annular groove in the inner face of head 16 receives the end of support 9 so that the resistor is carried by and between 80 heads 12 and 16.

Contact head 16 carries a circularly arranged series of fixed contacts 18 which may be in the form of flat headed bolts passing through head 16. Fixed contacts 18 are 85 connected to different points on the coil of resistor 8 by taps 19. Suitable nuts 20, threading upon the projecting shanks of contacts 18, serve to anchor the contacts in place in the contact head and may be utilized to clamp the ends of the respective taps 90 19 thereto. Contact head 16 has an axial hole therethrough and into this hole a metal bushing 21 fits. Bushing 21 may be provided with fins or projections 22 to prevent 95 the same from turning.

The adjacent end of housing 10 is provided with an insulating head 25 which may be secured in place by screws 26 and has an axial hole 27 therethrough. A hollow 100 handle extends through hole 27 and the bore of bushing 21. This handle comprises a metal tube 28 and knurled knob 29. Knob 29 may be made of suitable insulating material secured to tube 28 by a screw 30.

A collar 31 is secured to tube 28 by a screw 32. Collar 31 has a movable contact 33 rigidly secured thereto. Movable contact 33 may be in the form of a copper brush whose outer end is adapted to friction- 105 110

ally engage the flat heads of fixed contacts 18. The turning of knob 29 will rotate brush 33 over the fixed contacts. A metal washer 34 may be interposed between head 5 25 and collar 31. A stop 35, in the form of a screw secured in head 16, will serve to limit the rotation of the handle and contact brush 33.

One end of resistor 8 is connected to a 10 terminal 36 which may take the form of a bolt secured to support 9. Bushing 21 is provided with a suitable terminal such as a screw 37.

This rheostat may be installed by cutting 15 only one conductor of the service cord and anchoring one of the severed ends to terminal 36 and the other severed end to terminal 37. The uncut conductor passes directly through the rheostat. Resistor 8 is 20 thus interposed in the circuit, between the power source and the power consuming appliance, and the amount of resistance may be varied by rotating knob 29.

Fig. 4 shows a longitudinal section of a 25 modified type of rheostat. In this rheostat the resistor is in the form of a rod 45 of a suitable resistance material, such as carbon. The terminal arrangement for the connection of the service cord sections is also modified. This rheostat has a tubular housing 46 and closing heads 47 and 48 somewhat similar to those previously described. Heads 47 and 48 are provided with sockets 30 for receiving the ends of resistance rod 45 35 to support the same.

Head 47 has an axial hole therethrough for accommodating an operating handle. This handle comprises an exteriorly threaded metal tube 50 and a knurled operating 40 knob 51 secured thereto. Head 50 carries two pin receptacle terminals 52 and 53 of any approved design.

A disc shaped support 54, of suitable insulating material, is secured in housing 46. 45 This support carries a metal nipple 55 which journals one end of tube 50. A screw 56 serves as a terminal for one of the supply conductors. The other supply conductor may be connected to receptacle terminal 52. 50 Receptacle terminal 53 is connected to resistance rod 45 by a lead 57.

Tube 50 has a threaded nut 58 mounted thereon. Nut 58 carries a contact spring or brush 59 which engages the surface of resistance rod 45. When knob 51 is turned it rotates tube 50 and nut 58 moves toward one or the other end of the housing. The movement of nut 58 carries spring or brush 59 along rod 45 and varies the resistance in 60 the circuit.

The delivery section of the service cord

may be provided with a suitable pin connector 60 which fits receptacles 52 and 53 to extend the service cord. With this type of rheostat both conductors of the supply cord are cut when installing the same. Both sections of the service cord terminate and are interconnected at the rheostat.

The rheostats herein shown form compact and reliable variable resistances for controlling the current to an appliance. One cord section leads into the rheostat through the axially positioned resistance controlling handle and the other cord section extends the circuit beyond the rheostat. The rheostat is, in effect, mounted in the service cord and may be suspended thereby near the operator or may be moved about so as to be easily accessible to the operator. It may be readily connected to and disconnected from the supply mains and various appliances.

Having described my invention what I claim as new and desire to secure by Letters Patent, is:—

1. A rheostat comprising an insulating tubular member, a resistance element wound thereon, an insulating head secured to one end of said member, a plurality of contacts on said head, connectors from said contacts to points spaced at intervals on said element, a sleeve manually rotatable relative to said member, a contact maker electrically and mechanically connected to said sleeve and rotatable thereby, an insulated conductor extending through said sleeve and said member, and a pair of conductors adapted to be in electrical circuit with said first named conductor, one of said last named conductors being secured to one end of said resistance element and the other being electrically connected to said contact maker.

2. A rheostat comprising an elongated tubular casing, a resistance extending longitudinally within the casing, a sleeve manually rotatable relative to said casing and said resistance upon the axis of said casing, an electrical contact brush electrically and mechanically connected to said sleeve and arranged to move when said sleeve is rotated to electrically connect said brush progressively with successive longitudinal portions of said resistance, an axially bored knob fixed to said sleeve exteriorly of the casing for turning the sleeve and for admitting conductor cords to the interior of the casing and electrical connecting terminals associated with said resistance and with said sleeve.

In testimony whereof I hereunto subscribe my name.

ROLLAND H. MAXSON.
